(57) CLAIM

We claim the ornamental design for an elongated tissue dispensing box with a base, as shown and described.

DESCRIPTION

FIG. 1 is a perspective view of an elongated tissue dispensing box with a base in accordance with the present design. FIG. 2 is a perspective front view thereof.

FIG. 3 is a perspective back view thereof.

FIG. 4 is a perspective side view thereof.

FIG. 5 is a top view thereof; and,

FIG. 6 is a bottom view thereof.
